Int. Cl. D4—99; D9—99
U.S. Cl. D33—17

FIGURE 1 is a perspective view of a container for a brush incorporating one embodiment of my new design and showing the container as it appears when viewed from above and in front of the container.

brush depicted in FIGURE 7, showing the container as it appears when viewed from below and to the rear of the container.

The characteristic features of my design reside in the surface patterns shown, in combination with the bow.

This application is a continuation-in-part of my pending application Ser. No. D8,687, filed Sept. 22, 1967 and now abandoned.

I claim:

The ornamental design for a container for a brush, substantially as shown and described.
